UNITED STATES PATENT OFFICE.

WILLIAM THOMAS BLACKWELL, OF VERONA, NEW JERSEY, ASSIGNOR TO WESTINGHOUSE LAMP COMPANY, A CORPORATION OF PENNSYLVANIA.

REFLECTOR.

1,381,103.

Specification of Letters Patent. Patented June 14, 1921.

Application filed March 27, 1919. Serial No. 285,463.

To all whom it may concern:

Be it known that I, WILLIAM THOMAS BLACKWELL, a citizen of the United States, and a resident of Verona, in the county of 5 Essex and State of New Jersey, have invented a new and useful Improvement in Reflectors, of which the following is a specification.

This invention relates to reflectors, and, 10 more particularly, to those useful in industrial lighting and adapted to be used with an incandescent lamp.

At present the most common form of reflector used in industrial lighting is a direct 15 lighting fixture of the porcelain enameled steel type, having one or more reflecting surfaces. This type reflector recommends itself for this special field of illumination because of its durability and the elimination of 20 glare, although the efficiency of such a reflector is but approximately 70% of the total light flux of the incandescent lamp. The loss of 30% in light is caused by the absorption of the reflecting surface.

25 Glass reflectors, although they give a certain amount of diffused light and a somewhat higher efficiency than an opaque reflector, have been found unsuitable for industrial lighting because of their liability to 30 breakage through accidental contact with foreign objects, and because they do not effectively shield the eye from glare.

An object of the invention is the provision 35 of a composite reflector of rugged construction, which produces a direct lighting effect, having an intensity substantially equal to a reflector of the porcelain enameled type, and also gives a diffused lighting effect such as is obtained by a glass reflector.

40 Another object of the invention is the provision of a reflector having a greater light reflecting efficiency than the present forms of metallic reflectors used in direct lighting, and at the same time possessing the advantages thereof.

I accomplish these objects by providing a composite reflector, the lower part of which may be comprised of porcelain enameled steel and the upper portion constituted of a 50 light diffusing material, such as glass. I have found that a reflector, embodying this construction, has an efficiency of substantially 80%.

Other objects of the invention relate to 55 the combination and construction of parts

hereinafter described and set forth in the appended claims.

In the accompanying drawing Figure 1 is an elevation, partly in section, of a reflector embodying my invention.

60

Referring to the drawing, it will be seen that the reflector shown is comprised essentially of a fitter 1, a light diffusing element 2, and a shield or skirt 3 of enameled steel. The skirt 3 is preferably provided with a 65 deep cutoff angle and a reinforced lower edge. The upper edge of the skirt 3 is provided with an inwardly bent portion 4, which is adapted to engage the lower portion of the light diffusing element 2. There 70 is provided a retaining member 5, which may consist of a thin piece of sheet metal, or the like, suitably attached to the inner surface of the skirt 3, and in co-operative position with the bent-over portion 4, so that 75 the element 2 may be firmly held in the groove formed by the parts 4 and 5. The retaining member 5 may be pressed into contact with the light diffusing element 2 by any suitable instrument, care being taken 80 not to fracture the same.

The light diffusing element 2 may consist of any kind of glass such as opal, opalescent, prismatic, and the like. The amount of diffused light obtained will vary with the density of the glass used, which is in accordance 85 with the well established principle that the greater the density of the glass the less the diffusion of the light. It is likewise true that the more light diffused by the element 90 2, the less light there will be reflected, and, vice versa, the more light reflected, the less light there will be diffused. It, therefore, follows that the kind and density of the glass selected for the element 2 will be controlling in the amount of light diffused or reflected, and may vary under different service conditions. It is preferable that the element 2 be of more than one contour as better distribution of the light may be obtained 95 from such a configuration. Practice would indicate that the shape illustrated is very efficient when the reflector is used in conjunction with the so-called Mazda "C" type lamps.

100 The fitter 1 may be locked to the upper portion of the element 2 by means of a flange 6 and a resilient ring 7, which is confined in a recess located at the base of the fitter 1. If desired, a washer 8, of fiber or 105

like substance, may be placed intermediate the contacting edge of the glass element and the ring 7. It is obvious that the fitter 1 may be made of sheet metal or a fibrous composition, since it performs no function in the reflection of the light.

It is obvious that the reflector contemplated by my invention, aside from its reflecting qualities, may be regarded as of the so-called knocked-down construction. For example, the reflector illustrated may have the fitter 1 detached therefrom prior to its use by the customer, which feature permits the reflector being placed in a smaller package than if made of a single part. Still further advantage may be taken of this knocked-down construction by packing the glass element 2 within the skirt 3, the latter affording protection for the former. Such a method of shipping is obviously feasible inasmuch as the elements 1, 2, and 3 have a telescopic relation to each other, and can readily be assembled by the user.

From the above description it will be apparent that a reflector embodying my invention will give a certain amount of light in the upper hemisphere, and, at the same time, give a light in the lower hemisphere substantially equal in intensity to that obtained from present forms of metallic reflectors. Because of this feature, my reflector may be found useful for purposes other than in industrial lighting. It will also be noted that the telescopic construction of my reflector makes it attractive to the trade from the standpoint of business economies.

While I have herein shown and particularly described a preferred embodiment of my invention, I do not wish to be limited to the precise details of construction illustrated, as changes may readily be made without departing from the spirit and scope of the invention.

What is claimed is:

1. A composite reflector comprising a porcelain enameled steel portion, an opal glass portion adjacent thereto, and a supporting means for the reflector, the shape and quality of the glass constituting the glass portion being such that the distribution and intensity of the light in the lower hemisphere is substantially equal to the distribution and intensity of the light obtained from an entirely opaque reflector having a similar configuration.

tion, while the light cast in the upper hemisphere is an appreciable percentage of the total lighting efficiency of the reflector.

2. A composite reflector comprising a porcelain enameled steel skirt portion provided with a deep cutoff angle, a glass translucent portion having a design embodying a plurality of contours and adapted to engage one of the edges of the said skirt portion, and a supporting fitter member adjacent to said translucent portion, the design and the glass constituting the translucent portion being such that the distribution and intensity of light in the lower hemisphere is substantially equal to the distribution and intensity of the light obtained from an entirely opaque reflector having a similar configuration, while the light cast in the upper hemisphere is an appreciable percentage of the total lighting efficiency of the reflector.

3. A composite reflector comprising a lower skirt opaque reflecting portion provided with a deep cutoff angle, a translucent portion adjacent to said opaque portion, the said translucent portion functioning as a light diffuser and as a reflector, and a fitter member adjacent to said translucent portion, the design and the material constituting the translucent portion being such that the distribution and intensity of the light in the lower hemisphere is substantially equal to the distribution and intensity of the light obtained from an entirely opaque reflector having a similar configuration, while the light cast in the upper hemisphere is an appreciable percentage of the total lighting efficiency of the reflector.

4. A composite reflector comprising an opaque reflecting portion, and a translucent portion adjacent thereto, the said translucent portion functioning as a light diffuser and as a reflector, the materials, configuration and relation of said portions being such that the distribution and intensity of the light in the lower hemisphere is substantially equal to the distribution and intensity of the light obtained from an entirely opaque reflector having a similar configuration, while the light cast in the upper hemisphere is an appreciable percentage of the total lighting efficiency of the reflector.

In testimony whereof, I have hereunto subscribed my name this twentieth day of March, 1919.

WILLIAM THOMAS BLACKWELL.
